United States Patent Office.

REYNOLDS T. REED, OF BINGHAMTON, NEW YORK.

Letters Patent No. 70,017, dated October 22, 1867.

IMPROVED MOP-WRINGER.

The Schedule referred to in these Letters Patent and making part of the same.

TO ALL WHOM IT MAY CONCERN:

Be it known that I, REYNOLDS T. REED, of Binghamton, in the county of Broome, and State of New York, have invented a new and useful Improvement on Mop-Wringers; and I do hereby declare that the following is a full, clear, and exact description of the construction and operation of the same, reference being had to the accompanying drawings making a part of this specification, in which—

Figure 1 is a perspective view, representing it attached to the pail ready for operation.

Figure 2 shows the apparatus as detached from the pail.

Similar letters of reference indicate corresponding parts in each figure.

The object of this invention is to construct a mop-wringer which shall answer all the purposes of those in ordinary use, and which shall be less liable to get out of order, less complicated and expensive, and more compact and portable.

The nature of my invention consists in the employment of two rollers, connected with a frame placed inside and secured to the rim of a vessel or pail, and held in position by brackets and thumb-screws, one of said rollers being pivoted in the top of two upright pieces, and the other in the free ends of two spring-arms attached to their lower ends, thereby keeping the rollers apart for the reception of the mop, they being drawn together by means of a flexible wire or cord, running over pulleys and connecting with a foot-piece on the outside of the pail.

I construct the rollers A A of wood or other suitable material, and connect them with a frame, B B, consisting of two upright pieces and two spring-arms, C C, which are attached at their lower ends near the bottom of the pail, and project a little above its edge, connected by cross-pieces. One of said rollers works on pivots in the free ends of the spring-arms, and the other in the projecting ends of the upright pieces. These spring-arms are set at an angle with the upright pieces, so that the rollers may stand apart sufficiently to receive the mop, and are drawn together by means of a flexible wire or cord, D, running over pulleys E E at the top of the projections of the frame B B, the ends of which cord are attached to the spring-arms, all being operated by pressure upon the foot-piece F, which is attached to the cord on the outside of the vessel or pail. The frame B B is supported on the pail by the brackets G G, and secured in position by thumb-screws H H. When the mop requires wringing it is dropped between the rollers, and the foot is applied to the foot-piece, which draws the rollers together. It is then drawn out, the foot holding the pail in its place during the operation. As the frame and rollers are placed inside of the vessel it makes it much more compact and portable than others in use. It is also more simple in its construction, consequently less liable to derangement, less expensive, and can be more economically and beneficially enjoyed by the public.

I therefore disclaim all interference with others which may be in some respects similar to my improvement, and confine myself only to its novel features.

Having thus described my invention, what I claim, and desire to secure by Letters Patent, is—

The combination of the frame B B, consisting of the upright pieces and spring-arms C C, with the rollers A A, wire or cord D, all operating within the compass of the area of the pail, constructed substantially as herein described, and for the purpose set forth.

REYNOLDS T. REED.
